CONTACT ASSEMBLY FOR DOUBLE-SUR-FACED RECTIFIER ELEMENTS

Carl C. Hein, Forest Hills, Pa., assignor to Westinghouse Electric & Manufacturing Company, East Pittsburgh, Pa., a corporation of Pennsylvania

Application August 25, 1938, Serial No. 226,646

4 Claims. (Cl. 175—366)

My invention relates to dissymmetrical junctions for solid electrical conductors and, in particular, to electrical rectifiers of the contact type.

One object of my invention is to provide a structure in which electrically conductive plates may form dissymmetrically conductive junctions with coatings of other material covering both of their opposite surfaces.

Another object of my invention is to provide a convenient structure for mounting a plurality of plates of the sort described in the preceding paragraph for connection into an electric circuit.

Still another object of my invention is to provide a convenient, economical and readily manufactured structure for assembling oxidized copper plates to employ both of their opposite surfaces as rectifying junctions in an electrical circuit.

Still another object of my invention is to provide a structure of the type referred to in the two preceding paragraphs in which radial extensions from certain of the plates provide a convenient, economical and readily manufactured means for dissipating heat either by fluid-stream cooling or by natural convection.

A still further object of my invention is to provide structures of the type referred to in the preceding paragraphs with arrangements for enclosing the dissymmetrical junctions to protect them from contact with the atmosphere of the room in which the apparatus is employed.

Other objects of my invention will become apparent from reading the following description taken in connection with the drawings, in which: Figure 1 is a view in mid section and Fig. 2 is an end elevation of a copper oxide rectifier assembly embodying the principles of my invention;

Figs. 3 and 4 are, respectively, views of opposite sides of a unit assembly of the type employed in the complete rectifier shown in Figs. 1 and 2, a portion of the plates in Figs. 3 and 4 being shown as cut away to better illustrate the structural details;

Fig. 5 is a view in section of a modified form of unit assembly which provides for preventing access of the surrounding atmosphere to the oxidized copper plate which forms the foundation of the rectifier unit; and

Fig. 6 is an end view and Fig. 7 a view in section of a unit assembly suitable to replace the unit shown in Figs. 3, 4 and 5 when it is desired to provide for increased or artificial cooling of the rectifier.

As is illustrated by basic Grondahl Patent No. 1,640,335, it has been customary in the past to

build copper oxide rectifiers by assembling a plurality of annular oxidized copper washers on a through-bolt. In these assemblies, one side of the copper washer was freed of oxide and constituted one terminal of a disk unit. The other terminal of each disk unit was a plate of lead which was pressed into contact with the remaining oxidized side of the disk with considerable force in order to insure good electrical contact thereto. Substantially any desired number of such washers were mounted on an insulating tube covering the through-bolt, but it was found impracticable to make the outer diameter of the washers greater than about 1½ inches, and the latter size has become pretty much a commercial standard. A single washer of this size could provide a direct-current output of about 0.4 ampere when provided with cooling fins, and where greater current than this was desired, it was the practice to connect a number of such assemblies of washers in multiple with each other.

Such multiple arrangements, however, leave much to be desired as to economy, both of manufacture and cost, and of installation-space, and the arrangement which I describe below makes it possible to obtain rectifiers of substantially higher current output while using but a single through-bolt assembly of rectifier disks of larger outside diameter. I accomplish this result by substituting for the lead contact plate on a single side of the copper disk a coating of sprayed metal covering a large fraction of both faces of a copper disk in which almost the entire surface has been oxidized. In this way, I avoid the necessity of maintaining high compressive forces necessary where lead contact plates are used, but nevertheless retain the convenient and readily manufactured circular disk and through-bolt method of assembly which characterized the earlier types of commercial rectifiers.

With the foregoing principles in mind, Fig. 1 shows a through-bolt 1 which may be of steel and which is covered with an insulating sleeve 2 of fiber or other desirable insulating material. On this sleeve there are shown as mounted a plurality, e. g., four, of individual rectifier units. It will be recognized that the number of such units depends upon the voltage to be rectified and that any desired number may be mounted on the above-described through-bolt structure in the same way as are the four units shown in Fig. 1.

Each of the rectifier units comprises a copper plate 3 which may conveniently be of circular form and have a central hole which just fits the outer surface of the sleeve 2. The copper

plate 3 may be manufactured by the processes described in the above-mentioned Grondahl Patent No. 1,640,335 and Geiger Patent No. 1,892,382, except that the oxide 4 should be formed upon both faces of the copper disk. The central hole of the disk may be slightly counterbored, at least on one side, to remove the oxide for a radial distance equal to the thickness of a metal spacing sleeve 5. The opposite faces of the above-described oxidized disk are then coated by a Schoop spray or the like (preferably after application of a coating of colloidal graphite to the oxide surface) with a coating of tin, zinc, silver or other desirable metal. As still another modification, the oxide surface may be metal coated and then be provided with plates 6 of steel, tin or zinc superposed thereon. As will be evident from the end view in Fig. 2 and from the detailed views in Figs. 3 and 4, the metallic coating when used should be applied so as to leave uncovered an annular rim at the outer edge of the disk. On one side of the disk 3, shown in Fig. 4, the plate 6 or the coating is so formed as to leave an uncovered rim 7 about the central hole, while in the other side of the disk 3 a fishpaper washer 8 may be applied to cover any rim of bare copper which may exist around the central hole, and the plate 6 or the sprayed coating is then made to extend radially inward to the edge of the central hole. As is shown in Fig. 1, this permits the assembly of two (or more) rectifier units on the insulating tube 2 in such a position that the metal sleeves 5 space them apart and make an electrical contact from the central rim 7 of bare copper on one disk 3 to the metal sheet 6 about the central hole on the adjacent disk unit. An electrical contact-bar 9, sandwiched between the metal sleeves 5 at the middle of the structure, forms a convenient means for conducting current to external circuits from the copper of the middle pair of copper disk units. Four (or any desired even number) of the aforesaid rectifier units having been assembled on the insulating sleeve 2, the through-bolt 1 may be placed in position with a pair of insulating end sleeves 11, end washers 12 and spring washers 13 for rigidly holding the assembly in position when the nut 14 is screwed up.

In the form shown in Figs. 2, 3 and 4, any desired number, such as three, spring clips 15 may be used to make contact between the opposite plates 6 (or sprayed metal coatings where the latter alone are used) on each unit assembly, and, if desired, these clips may be soldered in position to hold each unit together before it is placed in final position on the insulating sleeve 2.

Where it is desired to enclose the copper disk 3 from contact with the atmosphere of the room in which the rectifier is to operate, the plates 6 may (except where coating 4 is so thick as to render it unnecessary) have their outer edges bent outward so as to insure that they do not touch the edge of the copper plate 3, and then bent inward so as to touch at their outer periphery. The outer peripheral seam thus produced should be sealed gas-tight, e. g., by soldering it. These covering plates may be alike except that one of them which is contiguous to the side on which the above-mentioned fishpaper washer is used should extend radially inward into contact with the insulating sleeve 2, while the other covering disk should have a central hole larger in diameter than the connecting ring 5, so that it does not make contact with the latter. The metal rings 5 should then each be covered by a ring of in-

sulating material which encloses them from the external atmosphere, and this ring of insulating material should have an outside diameter larger than the inside diameter of the covering plate last mentioned. Alternatively to the use of a ring of insulating material to cover the external surface of the connecting sleeve 5, the latter may be coated with a suitable varnish or lacquer, and such a protecting coating of varnish or lacquer may also be applied to seal the joint at each end of the insulating ring when the latter is used as a cover for the connecting sleeve 5. Where the rectifier is intended for use in atmospheres containing acid or other corrosive gases, the surface of the cover plates and of the through-bolt may be covered with a non-corrosive protecting coating.

Where it is desired to provide extra efficient cooling of the rectifier, the plate 6 on the side adjacent the above-mentioned fishpaper washer 8 may be considerably larger in diameter than the copper disk 3. Such a cooling plate may be provided for each unit rectifier and will furnish a large cooling surface which may make use either of fluid convection or natural circulation to dissipate the heat generated by current flowing through the rectifier. In such a case, the spring clips 15 illustrated in Figs. 2, 3 and 4 may be replaced by single springs 16 fastened at one end to the large diameter cooling plate 6 just described, and at the other end to the plate 6 on the opposite face of the unit.

Such a unit as is shown in Figs. 1 and 2 constitutes four half-wave rectifiers, the terminal 9 acting as a positive terminal for an external circuit when an alternating voltage is impressed from a transformer secondary 17 between terminals connected to the sprayed metal coatings or cover plates of the tube and rectifier units. Proper circuits for employing rectifier assemblies such as those above described are too well known in the art to require further detailed description.

Plates of other than circular periphery and having more than one through-bolt and hole therefor are within the scope of my invention.

To describe one specific embodiment of my invention in detail, the copper plates of Fig. 1 may be of sheet copper .050 inch thick by 4 inches in outside diameter and having a central hole $\frac{1}{2}$ inch in diameter. The cover plates 6 may be of sheet in about .010-.020 inch thick and $3\frac{1}{4}$ inches in outside diameter, the central hole of one set of such plates being of the same diameter as the central hole in the copper plate 3 and the central hole in the other set of cover plates being about $1\frac{1}{2}$ inches in diameter. The spring clip 15 may be of steel wire about .050 inch in diameter by $1\frac{1}{2}$ total inches long.

In the arrangement of Fig. 5, the dimensions of the copper plate 3 may be the same as those given above for Fig. 1. One cover plate may have a central hole of the same size as that in the copper plate 3, while the central hole in the other cover plates may have a diameter of about $\frac{1}{4}$ inch. These cover plates may be of the same material and thickness as those already described in connection with Fig. 1 and may have an outside diameter of about $4\frac{1}{2}$ inches. The spacing between the edge of the copper plate 3 and the nearest part thereto of the cover plates 6 should be about .010-.050 inch. The conducting sleeve 5 may have an external diameter of about $\frac{5}{8}$ inch and a length of about $1\frac{1}{8}$ inch. The insulating sleeve 18 in the Fig. 5 modification may have an external diameter of about $\frac{3}{4}$ inch.

It will be recognized that while I have described my invention as applied to a copper oxide rectifier, it is equally applicable to copper hemi-sulfide rectifiers or to other electrical circuit elements in which it is desired to utilize the properties of a junction between the surface of a disk or plate and a chemically different material in contact therewith. In compliance with the patent statutes, I have described one particular embodiment of my invention, but it will be recognized that the principles thereof are of broader application in ways which will be evident to those skilled in the art. I, accordingly, desire that the following claims shall be given the broadest interpretation of which their terms are capable in the light of the prior art.

I claim as my invention:

1. A contact rectifier unit comprising a copper plate having its opposite faces oxidized, a pair of metallic sheets respectively in contact with said oxidized faces, at least one hole having its walls free from oxide in said copper plate, one of said metallic sheets having its inner periphery separated from said hole by an annular insulating rim and the other of said sheets extending radially inward to form a hole having substantially the same size as said central hole.
2. A contact rectifier assembly comprising a plurality of units of the type specified in claim 1 mounted on an insulating sleeve passing through their central holes, and spacing sleeves of conducting material on said insulating sleeve

connecting the unoxidized walls of the hole in the copper plate of one unit with the metallic sheet of the adjacent unit.

3. A contact rectifier assembly comprising a plurality of rectifier units, each rectifier unit comprising a circular copper plate having its opposite faces oxidized except for a narrow rim of bare copper surrounding a hole therein, a metallic sheet in contact with each oxidized face of said copper plate except for an insulating rim surrounding said rim of bare copper, the respective said rectifier units being mounted on an insulating tube which passes through said hole of each of said rectifier units, a conductive metal sleeve surrounding said insulating tube between each pair of rectifier units and extending from the metallic sheet of one rectifier unit to the bare copper rim of the adjacent rectifier unit, means for exerting pressure parallel to the axis of said insulating tube to maintain said rectifier units in position thereon, and means for making an electrical connection to the metal ring between the middle pair of rectifier units and to the metallic sheet of each end rectifier unit.

4. The structure specified in claim 3 with the addition of a sleeve of insulation surrounding each said conductive metal sleeve and thick enough to contact the metallic sheet of the rectifier unit at each of its ends, the metallic sheet on each rectifier extending to form a closure around the outer edge of said copper plate.

CARL C. HEIN.
